CLAIM

The ornamental design for a pet hair collector, as shown and described.

DESCRIPTION

FIG. 1 is a front perspective view of the front, right, and top sides of a pet hair collector showing our new design;
FIG. 2 is a rear perspective view of the rear, left, and bottom sides thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof; and,

FIG. 8 is a right side view thereof.

The broken lines illustrate portions of the pet hair collector that form no part of the claimed design.
